UNITED STATES PATENT OFFICE

2,059,637

COOLER, HUMIDIFIER, AND AIR CIRCULATOR

Paul D. Good, West Lawn, Pa.

Application May 7, 1936, Serial No. 78,462

6 Claims. (Cl. 261—103)

The invention relates to a humidifier and air circulator and more especially to radiator humidifier and air circulator apparatus and cooler.

The primary object of the invention is the provision of an apparatus of this character, wherein the radiators of building heating systems can be incased and through the use of water supply a fabric sheet can be saturated therewith for the moistening of the heated air from each radiator and such moistened air circulated in the building and the water supply may contain an anti-septic solution which aids in the elimination of bacteria and unpleasant odors within an enclosure, room or building.

Another object of the invention is the provision of an apparatus of this character, wherein the construction thereof is novel in form and the same is automatic in the working thereof for humidifying and circulating heated air issuing from a radiator of a heating system within an enclosure.

According to medical science a considerable amount of disease and sickness occurring within a home during the winter months is attributed to the lack of humidity as well as the air from a heating system carrying bacteria and oftentimes unpleasant odors so to minimize these disturbances there has been devised the humidifier and air circulator which in the operation thereof eliminates bacteria and unpleasant odors and reduces diseases and sickness to a minimum as well as increasing the efficiency of the heating system by utilizing the dormant heat of the radiator of that system and a resultant saving in fuel consumption as well as preventing dry rot of the woodwork and the cracking of furniture by reason of the lack of moisture within the heated air, the apparatus being attractive in appearance when fitting a radiator of the heating system and is serviceable for homes, churches, schools, hospitals, factories or the like.

A still further object of the invention is the provision of an apparatus of this character, which is comparatively simple in its construction, thoroughly reliable and efficient in its operation, readily and easily applied to the radiator of the heating system, automatic in the working thereof, neat and attractive in appearance and comparatively inexpensive to manufacture and install.

With these and other objects in view, the invention consists in the features of construction, combination and arrangement of parts as will be hereinafter more fully described, illustrated in the accompanying drawing, which discloses the

preferred embodiment of the invention and pointed out in the claims hereunto appended.

In the accompanying drawing:

Figure 1 is a vertical longitudinal sectional view through the apparatus constructed in accordance with the invention.

Figure 2 is a vertical transverse sectional view through said apparatus.

Figure 3 is an enlarged fragmentary vertical longitudinal sectional view through the apparatus showing the water supply control and adjuncts.

Figure 4 is a sectional view on the line 4—4 of Figure 1.

Figure 5 is a sectional view on the line 5—5 of Figure 1.

Similar reference characters indicate corresponding parts throughout the several views in the drawing.

Referring to the drawing in detail, A designates generally a casing preferably made from sheet metal and is of a shape and size to fit over a radiator B of conventional type used in heating systems for buildings. The casing A has interiorly thereof a wire screen partition 10 built therein in any suitable manner to be located forwardly of the radiator B when the casing fits thereover. The top of the casing A carries a reticulated air outlet 11 as well as a vertically swinging damper 12. The front wall 13 of this casing A at the lower portion thereof is provided with perforations 14 forming air inlets to the interior of the casing forwardly of the screen partition 10. This partition provides a compartment 15 for the radiator B and a compartment 16 which at the upper portions thereof is formed with a water tank 17, the same being supported upon uprights 18, these are spaced from each other and extend to the floor line of an enclosure. The uprights 18 next to the floor line are formed with a shelf 19 upon which are arranged the stands 20 of electric fans 21 which are vertically adjustable and are located laterally spaced from each other the proper distance apart. These fans 21 are arranged in an electric circuit 22 including a thermostatic switch 23, a transformer 24, and a hand switch 25, respectively. The hand switch 25 is arranged in the circuit 22 to cut out the thermostat 23 as may be required and such switch 25 is carried exteriorly on one end wall of the casing A for convenient access.

In the lower portion of the compartment 16 and spread across the larger portion thereof between the screen partition 10 and the fans 21 is a reticulated absorbent sheet or curtain 26 which is

framed at 27 along the ends and bottom edges thereof while at the top edge are liquid feeder heads 28, these being reversely inclined and are joined with opposite sides of a distributor box 29
5 for communication therewith. Rising centrally from the distributor box 29 is a valve casing 30 with which is joined a delivery hose 31, the same being also joined with a discharge nipple 32 centrally of and depending from the tank 17. Included in the circuit 22 is an electric solenoid 33 for operating a cut off valve 34, the solenoid when deenergized being for the purpose of cutting off the supply from the tank 17 to the distributor box 29 in that the valve 34 is in closed position. On 10 energizing the solenoid 33 the valve 34 is automatically opened. This valve 34 fits the valve casing 30 for controlling the supply of liquid from the tank 17 to the distributor box 29. The valve casing 30 also has fitted therein a hand operable 15 regulating valve 35 which regulates the feed of liquid from the tank 17 to the distributor box 29 and such valve 35 is accessible from without the casing A at the front thereof for convenience in the handling of said valve.
20 25 The uprights 18 have connected therewith brackets 36 which cooperate with additional brackets 37 and 38, respectively, for the firm holding of the apparatus when the casing A encloses or incases the radiator B, these brackets being attached to the said radiator B. The bracket 37 is carried by the distributor box 29 while the brackets 38 are carried by the framing 27.

It is preferable to have the lower portion of the casing at 39 cut away for the inflow of air augmenting the admission of air through the perforations 14 in the front wall 13 of said casing A.

In the operation of the apparatus when the steam or hot water coming into the radiator reaches a temperature of approximately one hundred and forty degrees Fahrenheit the thermostat 23 turns on the electric current through the circuit 22 energizing the solenoid 33 for the automatic opening of the valve 34 which allows the liquid within the tank 17 to flow through pipe 31, distributor box 29 and heads 28 for saturating the sheet or curtain 26, the valve 35 being set for regulating the feed of the liquid for the desired humidity needed in the enclosure in which is present the radiator B. By the time the radiator is heated 40 throughout the sheet or curtain 26 and saturation is already beginning to vaporize the liquid absorbed. The operation of the fans 21 drives this vapor through the radiator B and preheating the same. These fans 21 also create circulation of 45 air in the room without any noticeable draft and thereby utilizing the dormant heat in the radiator with the result that the room or enclosure will be heated in half the time required under ordinary or normal conditions.

60 What is claimed is:

1. An apparatus of the character described comprising a casing having a wire screen partition interiorly thereof dividing it into several 65 compartments, one of the compartments accommodating a radiator of a heating system, a liquid supply tank in the other compartment, a liquid distributor box below said tank and having communication therewith, feeder heads extending from said box, an absorbent sheet associated with 70 said heads and depending therefrom, a feed regulating valve for controlling liquid flowing from the tank to said distributor box, and an electrically controlled cut off valve for opening and closing 75 the communication between the box and said tank.

2. An apparatus of the character described comprising a casing having a wire screen partition interiorly thereof dividing it into several compartments, one of the compartments accommodating a radiator of a heating system, a liquid supply tank in the other compartment, a liquid distributor box below said tank and having communication therewith, feeder heads extending from said box, an absorbent sheet associated with 5 said heads and depending therefrom, a feed regulating valve for controlling liquid flowing from the tank to said distributor box, an electrically controlled cut off valve for opening and closing 10 the communication between the box and said tank, and an electrically operated fan arranged in confronting relation to the absorbent sheet for 15 circulating air through the said radiator.

3. An apparatus of the character described comprising a casing having a wire screen partition interiorly thereof dividing it into several 20 compartments, one of the compartments accommodating a radiator of a heating system, a liquid supply tank in the other compartment, a liquid distributor box below said tank and having communication therewith, feeder heads extending 25 from said box, an absorbent sheet associated with said heads and depending therefrom, a feed regulating valve for controlling liquid flowing from the tank to said distributor box, an electrically controlled cut off valve for opening and closing 30 the communication between the box and said tank, an electrically operated fan arranged in confronting relation to the absorbent sheet for 35 circulating air through the said radiator, and a thermostat coacting with the electrically operated valve.

4. An apparatus of the character described comprising a casing having a wire screen partition interiorly thereof dividing it into several compartments, one of the compartments accommodating a radiator of a heating system, a liquid supply tank in the other compartment, a liquid distributor box below said tank and having communication therewith, feeder heads extending 40 from said box, an absorbent sheet associated with 45 said heads and depending therefrom, a feed regulating valve for controlling liquid flowing from the tank to said distributor box, an electrically controlled cut off valve for opening and closing 50 the communication between the box and said tank, an electrically operated fan arranged in confronting relation to the absorbent sheet for 55 circulating air through the said radiator, a thermostat coacting with the electrically operated valve, and a perforated front to said casing.

5. An apparatus of the character described comprising a casing having a wire screen partition interiorly thereof dividing it into several compartments, one of the compartments accommodating a radiator of a heating system, a liquid supply tank in the other compartment, a liquid distributor box below said tank and having communication therewith, feeder heads extending 60 from said box, an absorbent sheet associated with 65 said heads and depending therefrom, a feed regulating valve for controlling liquid flowing from the tank to said distributor box, an electrically controlled cut off valve for opening and closing 70 the communication between the box and said tank, an electrically operated fan arranged in confronting relation to the absorbent sheet for 75 circulating air through the said radiator, a thermostat coacting with the electrically operated valve, a perforated front to said casing, and a reticulated top to said casing.

6. An apparatus of the character described comprising a casing having a wire screen partition interiorly thereof dividing it into several compartments, one of the compartments accommodating a radiator of a heating system, a liquid supply tank in the other compartment, a liquid distributor box below said tank and having communication therewith, feeder heads extending from said box, an absorbent sheet associated with said heads and depending therefrom, a feed regulating valve for controlling liquid flowing from the tank to said distributor box, an electrically controlled cut off valve for opening and closing the communication between the box and said tank, an electrically operated fan arranged in confronting relation to the absorbent sheet for circulating air through the said radiator, a thermostat coacting with the electrically operated valve, a perforated front to said casing, a reticulated top to said casing, and brackets interiorly of the casing for firmly holding the same attached to the radiator. 5 10
